UNITED STATES PATENT OFFICE.

LELAND A. BABCOCK, OF OAK PARK, ILLINOIS.

CAN OPENER.

Application filed October 29, 1919. Serial No. 334,293.

To all whom it may concern:

Be it known that I, LELAND A. BABCOCK, a citizen of the United States, and a resident of Oak Park, in the county of Cook and State of Illinois, have invented certain new and useful Improvements in Can Openers, of which the following is a full, clear, and exact description.

The invention relates to can-openers.

One object of the invention is to provide an improved can-opener in which the knife is adapted to cut the side of the can in such manner that the burrs from the cut will be on the outside of the can, leaving the interior substantially unobstructed or without constriction in discharging the contents thereof. Another object of the invention is to provide an improved rotary can-cutter which is adapted for cans of different sizes.

Other objects of the invention will appear from the detailed description.

The invention consists in the several novel features hereinafter set forth and more particularly defined by claims at the conclusion hereof.

In the drawings: Fig. 1 is a side elevation of a machine embodying the invention. Fig. 2 is a front elevation, parts being shown in section. Fig. 3 is a vertical section through the cutter-head. Fig. 4 is an inverted plan of said head. Fig. 5 is a detail of one of the cutters and Fig. 6 is a detail section showing one of the cutters in operation. Fig. 7 is a perspective of the can-support.

A supporting bracket 8 is adapted to be secured to a table by bolts 9 and comprises a lower arm 10 adapted to support the table 11 on which the cans are held and an upper arm 12, to which is secured, by bolts 12^a, a frame provided with a central bearing 13 for the cutter-head shaft 14 and bearings 15 for a crank-shaft 16. A rotary cutter-head 17 is fixed to the lower end of the shaft 14 which is adapted to be driven by a gear-wheel 18 fixed to its upper end and a pinion 19 fixed to the shaft 16, which has a crank 20 secured to one end thereof. This cutter-head is provided on its under-face with a series of recesses 21, 22 and 23 adapted to receive the upper ends of cans of different sizes respectively. The table 11 is provided with a corresponding series of annular grooves 24, 25, and 26 to receive respectively the lower ends of the cans of corresponding sizes.

Cutters 27 are secured in the head, one being provided for each of the different sizes of cans. Each cutter is secured by screws 29 and is provided with a point 30 which is adapted to be forced through the can, and a cutting-edge 31 which is inclined in such direction that it will cut the can from the inside outwardly to cause the burr to be on the outside of the can, as shown in Fig. 6. This is an important characteristic, because when the can top has been removed, the entire contents can be discharged from the can. There is no obstruction resulting from an inwardly extending burr, such as there is when the cut is made in an inward direction or when the top is cut and a marginal portion is left on the can.

The head 17 is divided, as at 17^a, to form a body-section 17^b and a cutter-carrying section 17^c which is pivotally connected to the main portion of the head 17 by a pivot 34. The purpose of this pivotal connection is to permit the knife-carrying section 17^c to be forced inwardly to cause the knife to puncture and enter the side of the can before commencing the rotating operation. To facilitate the entry of each knife into the can, it is provided with point 30. As the cutter-head is rotated, the resistance of the can to the advance of the cutting edge 31 of the knife will tend to move the knife-carrying-section toward and hold it against the body-section, so that no locking-means will be necessary between the sections.

The table 11 is secured to a spindle 36 which is vertically slidable in the bracket 10 and a hub 37 on the underside of the table 11 is provided with a cam 38 which engages a lifting cam 39 which is provided with a handle 39^a and is rotatable around the spindle 36 to lift the table 11 so that the upper ends of cans of different sizes will be raised into their respective recesses in the rotary cutter-head. A lug 40 secured to the bracket 8 by a bolt 41 extends through a notch 42 in the table 11 to hold the latter against rotation.

The operation of the mechanism will be as follows: The bottom end of the can to be opened will be placed in the corresponding groove in the table 11 which will properly position the can for entry into the corresponding recess in the cutter-head and hold the lower end against lateral movement on the table. Next, the handle 39^a on the

cam 39 will be rotated to lift the can into the cutter-head, the knife-carrying section 17^b being swung upwardly so that the can will clear the knife 27 while it is being elevated. Next, the head-section 17^b will be forced downwardly and inwardly to force the point 30 of the cutter-blade in the recess, in which the upper end of the can is located, through the side of the can. Next, the crank 20 will be rotated while the can is held against rotation by the operator and this will cause the inclined edge 31 to cut the side of the can from the inside outwardly so that the burrs will be outside of the can. The upper end of the can will be confined against lateral movement in one of the recesses in the cutter-head so that the parts of the can may, if desired, be completely severed by a complete revolution of the cutter-head.

The invention exemplifies a can-opener comprising mechanism for rotating a knife relatively to the can and by which the side of the can is cut from the inside outwardly, also one which is adapted to operate upon cans of different sizes and in which the can is held so that the top may be completely severed from the body of the can.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. In a can-opener, the combination of a cutter-head having a socket to receive and fitting over one end of a can and formed of movably connected sections, and a blade carried by one of the sections and adapted to penetrate and cut the side of a can.
2. In a can-opener, the combination of a cutter-head having a socket to receive one end of a can and formed of pivotally connected sections, and a blade carried by one of the sections and adapted to penetrate and cut the side of a can.

3. In a can-opener, the combination of a cutter-head provided with a plurality of recesses of different diameters to receive cans of different sizes and formed of movably connected sections, and a knife for each can of different sizes and in which the can recess adapted to be forced into and to cut the side of the can.

LELAND A. BABCOCK
